UNITED STATES PATENT OFFICE

2,188,051

EXTRACTION PROCESS

Vernon Lantz, Oakland, Calif., assignor to Shell Development Company, San Francisco, Calif., a corporation of Delaware

Application November 1, 1937, Serial No. 172,207
Renewed December 4, 1939

5 Claims. (Cl. 196—13)

This invention relates to the extraction of various oils, such as mineral, vegetable, marine, animal, or ethereal oils, and particularly the higher molecular oils, to separate them into fractions having different properties.

It is known to extract such oils with liquid carbon dioxide at ordinary temperatures. Such a process is, for example, disclosed in the United States patent to Auerbach, No. 1,805,751. In such a process the ratio of quantities of the dissolved and undissolved fractions is limited by the solubility of the oil in the carbon dioxide, and is difficult to regulate except by varying the quantity of the carbon dioxide employed it being necessary to use a proportionately larger quantity of carbon dioxide to dissolve more oil. An increase in the temperature causes oils to be even less soluble in carbon dioxide, while the use of lower temperatures is not feasible because of the solidification of the oils. The use of larger quantities of carbon dioxide is, moreover, not practical because exceedingly large amounts of the solvent are required to effect the dissolution of an appreciable amount of oil therein, in view of the relatively low solubility of oil in carbon dioxide.

It is an object of the present invention to provide a process for the extraction of oils with a solvent containing a liquefied gas of the type of carbon dioxide, in which it is possible to vary the relative sizes of the extraction products without using prohibitively large quantities of the solvent. It is a further object of this invention to provide a process of the type described in which it is possible to produce a plurality of different fractions from the same initial stock in a simple manner. Other objects will be apparent from the following specification.

According to the present invention it was found quite unexpectedly that when a mixture of a liquid low molecular aliphatic hydrocarbon, which may be either normally gaseous or normally liquid, and liquid carbon dioxide is employed as a solvent for extracting higher molecular oils, the sizes of the phases produced may be nicely regulated by varying the ratio of the hydrocarbon and the carbon dioxide in the solvent, and that it is not necessary to employ proportionately larger amounts of carbon dioxide to increase the proportion of the oil which is dissolved in the solvent mixture. In fact, the results obtained in the process according to the present invention are so far contrary to those obtainable in the Auerbach process that an increase in the quantity of the carbon dioxide actually reduces the amount of oil dissolved, when

the ratio of the low molecular hydrocarbon to the oil being treated is maintained constant.

While it has heretofore been proposed to employ liquid paraffinic hydrocarbons in connection with other liquid selective solvents such processes did not permit the regulation of the sizes and qualities of the products produced over a wide range with the facility and in the manner of the present process, since in such processes, with a given amount of hydrocarbon diluent, the addition of larger quantities of the selective solvent, in general, effects an increase in the amount of oil dissolved, and the use of larger quantities of the paraffinic hydrocarbon diluent in such cases reduces the amount of oil dissolved in the solvent. This is contrary to the present process in which an increase in the amount of carbon dioxide lowers the quantity of oil dissolved and the paraffinic hydrocarbon diluent promotes the solubility of the oil.

Referring to Figure 1 of the drawings, an initial oil from tank 1 is fed via pump 2 to mixer 3, wherein it is mixed with a liquid paraffinic hydrocarbon diluent, such as propane, butane, or isopentane, and with liquid carbon dioxide, fed from tanks 4 and 5 via valves 6 and 7, the ratio of the diluent to the carbon dioxide being proportioned to dissolve the desired quantity of oil. The resulting mixture is fed to a phase separator, such as a centrifuge or settling chamber, indicated at 8, in which it is separated into a light liquid phase, withdrawn at 9, containing the greater part of the carbon dioxide and the diluent, and a heavier liquid phase, withdrawn at 10. The phases may be withdrawn continuously or intermittently. The latter fed to a flash pot 11 for the separation of the carbon dioxide, which is returned to the tank 5 via compressor 12 and condenser 13, the residual portion of the heavy phase being treated in the stripper 14 for the removal of the hydrocarbon diluent and any remaining carbon dioxide. The diluent is returned to the tank 4 via compressor 15 and condenser 16, and the undissolved oil passes to a receiving tank 17. The lighter phase withdrawn at 9 may be similarly treated for the recovery of the solvent mixture.

It is a feature of the present process that a relatively large proportion of the initial oil can be separated in the lighter phase without the use of large amounts of solvent. It is, therefore, possible to recover a relatively large amount of oil, such as, for example, from 40 to 90% in the lighter phase, and then to fractionate this dissolved oil further. In this operation, the dis-

solved oil is treated with a second solvent mixture containing the same or different components as the first solvent mixture, used in the first extraction step, but having a lower solvent power for the oil. When the components of the second solvent mixture are the same, the ratio of diluent to the carbon dioxide is preferably lower although it is also possible to cause phase separation by lowering the solvent power by increasing the temperature, or by removing a portion of the solvent mixture from the lighter phase. According to the preferred embodiments the separation of the light liquid phase into new phases is effected either by adding more liquid carbon dioxide to the light phase, or by adding both diluent and carbon dioxide, but more of the latter, or by lowering the concentration in the phase of the diluent.

As illustrated in Figure 1, the lighter phase may be brought to a higher pressure by a pump, and commingled with an added quantity of liquid carbon dioxide, fed via the valve 18, mixed in the mixer 19, and separated into new lighter and heavier liquid phases in the separator 20. As explained above, an added quantity of diluent may also be introduced via valve 21, whereby the dilution ratio is increased and a sharper fractionation is often effected. The light and heavy phases are withdrawn via valved lines 22 and 23, and freed from the solvent in flash pots 24 and 25 and strippers 26 and 27, as explained for the first heavy phase, the oil fractions being stored in tanks 28 and 29.

It should be noted that the successive operations described can all be carried out in a single tank provided with a stirring device and with means for intermittently or continuously drawing off the heavy phase and supplying carbon dioxide or a mixture of carbon dioxide and a diluent.

According to a modification of the process illustrated in Figure 2, the initial oil from the tank 30 is fed through pump 31 commingled with a diluent and carbon dioxide supplied from the tanks 32 and 33 at rates regulated by valves 34 and 35; after intimate mixing in the mixer 36, the resulting light and heavy liquid phases are separated in the separator 37, as described for Figure 1. The further treatment of the light phase according to Figure 2 follows the third of the above-mentioned preferred modes, that is, the light phase is fed to a flash pot 38 or other distilling apparatus via a throttling valve 39 for the separation of all or a portion of the diluent. The carbon dioxide will in most cases also be separated, since it is more volatile than most diluents. The mixture of carbon dioxide and diluent may be separated into its components; it is, however, often more economical to compress it in the compressor 40, cool it in the condenser 41, and introduce it ahead of the mixer 36 via reservoir 42 and valve 43. It is then only necessary to feed sufficient materials through the valves 34 and 35 to make up the deficiency of the solvent mixture which is not recovered from the light phase in the flash pot and which is dissolved in the heavy phase.

The residual portion of the lighter phase is withdrawn from the flash pot and mixed in the mixer 44 with a solvent mixture supplied via valves 45 and 46, different from that flashed off at 38, whence it passed to the phase separator 47. The resulting light and heavy liquid phases are withdrawn from the separator via valves 48 and 49, and treated in the flash pots 50 and 51 for

the recovery of the carbon dioxide, and in the strippers 52 and 53 for the recovery of the diluent and such carbon dioxide as is not separated in the flash pots, the oil fractions being withdrawn at 54 and 55. The carbon dioxide and diluent are returned to the storage tanks via compressors 56 and 57 and condensers 58 and 59.

The heavy phase from the separator 37 is withdrawn via a valve 60, and may be treated as shown in Figure 1. It is, however, possible to extract further quantities of oil from this phase. For this purpose, the heavy phase is commingled with carbon dioxide and a diluent, fed via valves 61 and 62, mixed therewith in the mixer 63, and separated into light and heavy phases in the separator 64. The light and heavy phases, withdrawn via the valves 65 and 66, are treated in the flash pots 67 and 68 and strippers 69 and 70 for the separation of the solvent mixture, and the oil fractions are withdrawn from the process at 71 and 72.

The process may also be practiced in a countercurrent manner, as illustrated in Figure 3. In this figure, 100 represents a countercurrent contact zone, such as a packed tower, or a contact apparatus provided with mixing and phase separating devices. The initial oil from the tank 101 is fed via a pump 102 to one end of the contacting zone, and a solvent mixture is fed to the other end via line 103. This solvent mixture contains the liquid paraffinic hydrocarbon diluent and the carbon dioxide in the ratio necessary to dissolve the desired proportion of the initial oil, and may be obtained by means of interconnected proportioning pumps 104, 105, supplied from tanks 106, 107.

In the contact zone 100 the solvent and oil flow countercurrently, producing a light extract phase, withdrawn at 108, and a heavier phase containing the undissolved oil, withdrawn at 109. The contact zone 100 may, if desired, be provided with temperature regulating means, such as coils 110, whereby a temperature gradient obtains. The temperature near the point at which the solvent mixture is introduced is preferably lower than that at which the initial oil is introduced.

The withdrawn phases may be further fractionated, either in the manner described above according to Figures 1 and 2, or in another countercurrent treatment. If the fractions produced in the zone 100 are to be withdrawn from the process, they are treated in flash pots 111, 112 and in strippers 113, 114 for the separation of the solvent mixture, and fed to receiving tanks 115 and 116. The recovered carbon dioxide and diluent are, respectively, returned to the tanks 107 and 106 via compressors 117, 118, and condensers 119, 120.

As the diluent, any solvent rich in lower aliphatic hydrocarbons may be employed, such as light naphtha, light gasoline fractions, etc., which may, moreover, contain higher boiling constituents. I prefer to employ a diluent containing at least 75% of paraffinic hydrocarbons containing less than seven carbon atoms which can be liquefied. Thus, ethane, propane, butane, isobutane, pentane, iso-pentanes, and hexanes constitute my preferred diluents. These hydrocarbons may, moreover, be employed alone, without the presence of higher boiling hydrocarbons or of methane. I prefer, moreover, to employ the branched chain hydrocarbons, particularly isobutane and iso-pentanes, or fractions containing over about 75% of the same.

The process may be carried out at ordinary

temperatures, preferably between about 0° C. and the critical temperature of carbon dioxide, although somewhat lower temperatures may also be employed, limited by the solidification of the 5 oils.

The ratio of the diluent to the carbon dioxide, and the ratio of the solvent mixture to the oil may be varied within wide limits, and will be apparent from the examples presented below. As 10 was pointed out above, an increase in the ratio of carbon dioxide to diluent decreases the quantity of oil extracted. The use of a larger ratio of solvent mixture to oil necessitates the use of a higher concentration of carbon dioxide in the 15 solvent. This frequently enhances the selectivity of the solvent mixture, but the use of larger quantities of solvent necessitates the use of larger equipment for handling the materials and for recovering the solvent.

15 It is not necessary to employ the same diluent in all of the stages. Thus, in successive stages further quantities of diluent of a different molecular weight may be added, together with the carbon dioxide, or the first diluent may be removed, 20 and the different diluent employed in a later stage. In general, it is preferable when employing different diluents, to use successively lower molecular diluents when treating successive lighter liquid phases. For example, the first light 25 phase in Figure 1 may be produced by employing a mixture of equal parts by weight of isopentane and carbon dioxide. Propane and carbon dioxide may then be introduced to effect a further separation in the separator 20. Similarly, in Figure 2, isopentane or butane may be 30 used in the separation effected in the stage 37, and a mixture of carbon dioxide with ethane or propane may be used in the separator 47. Conversely, it is desirable to treat the heavier phase 35 with the same or with a higher molecular diluent than was employed in producing that phase. Thus if butane was employed to produce the first heavy phase in the separator 37 of Figure 2, a pentane or a hexane may be employed in the 40 separator 64.

Example I

A Coalinga residual had the following properties:

50 Specific gravity, d_{40}^{20} 0.9784
 Refractive index n_D^{20} 1.5444
 Viscosity, seconds Saybolt Universal at 100° F 15,850
 Viscosity, seconds Saybolt Universal at 210° F 247.5
 55 Viscosity index ..... -3

Several samples of this oil were each separately dissolved in isopentane, and liquid carbon dioxide was added to the resulting solution in the 60 proportions shown in Table I, all quantities being parts by weight based on 100 parts by weight of the original sample. The resulting mixture was agitated for an hour and allowed to stand for two hours, forming two liquid layers, following 65 which these phases were separated and freed from the isopentane and carbon dioxide. During these operations the mixture was held at a pressure of 850 lbs. per sq. in. gauge and the temperature was held at about 20°-22° C. The heavier phase 70 contained the undissolved oil, together with between 5 and 10% of the solvent mixture; its properties are tabulated in Table I. The lighter phase contained most of the solvent and the dissolved oil; its properties are tabulated in Table 75 II, the run numbers being the same as in Table I:

Table I

Run No.	Amount of solvent added		Amount dissolved in light phase	Properties of undissolved oil		
	Diluent	CO ₂		Specific gravity d_{40}^{20}	Viscosity seconds at 210° F.	Viscosity gravity constant
1	190	221	77.6	1.0471	20,785	0.947
2	190	253	59.4	1.0299	4,208	0.943
3	190	536	32.8	1.0048	983	0.930
4	190	929	26.5	0.9966	637	0.925

Table II

Run No.	Properties of dissolved oil					
	Specific gravity d_{40}^{20}	Refractive index n_D^{20}	Viscosity, seconds—		Viscosity	Viscosity gravity constant
			At 100° F.	At 210° F.		
1	0.9618	1.5380	4,859	136.2	2	0.901
2	0.9482	1.5287	2,008	90.6	12	0.891
3	0.9318	1.5177	747	62.2	29	0.886

It will be noted that as progressively larger quantities of liquid carbon dioxide are used the amount dissolved therein decreases, and that the dissolved oil is progressively more paraffinic and less viscous, while the undissolved residual oil becomes less aromatic or naphthenic and less viscous. My process, therefore, effects a separation both on the basis of molecular size and on chemical structure, in that the solvent mixture preferentially dissolves oils by lower viscosity, i. e., oils having smaller molecules, and oils which have lower internal pressures, i. e., oils which are more paraffinic in nature, as indicated by the refractive index, viscosity index, and viscosity gravity constant.

For the purposes of comparison, two samples of the same initial oil were treated with pure liquid carbon dioxide in the manner described above, with the following results:

Table III

Run No.	5	6
Conditions in system at phase equilibrium:		
Pressure, lb. per sq. in. gauge	840	1100
Temperature, °C.	21	31
Composition of light phase:		
Weight of oil, grams	Less than 8	Less than 2
Weight of carbon dioxide, do	1,945	1,185
Solubility of oil in carbon dioxide, percent	Less than 0.41	Less than 0.2

It will be noted that pure carbon dioxide dissolved only very small quantities of oil, and that the use of pure carbon dioxide for the fractionation of oils would require excessive quantities of solvent to dissolve an appreciable amount of oil.

Example II

A Coalinga residual oil had the properties shown in the last column of Table IV.

Two samples of this oil were separately treated with different solvent mixtures, by introducing the oil continuously into the uppermost stage of a six-stage countercurrent column equipped with alternate mixing and settling zones, and introducing the solvent mixture consisting of isopentane and carbon dioxide continuously into the lowermost stage the composition and amount

5

70

75

of solvent being shown in the table. The temperature was maintained constant at 30° C., and the pressure was sufficient to liquefy the solvent. About 90 to 95% of the solvent mixture was present in the lighter phase which contained the dissolved oil. The quantities given are parts by weight based on 100 parts by weight of the original oil, and the quantity for the solvent is the rate of introduction of the solvent, based on the rate of introduction of the oil. The properties of the oil obtained from the phases withdrawn at the opposite ends of the column are shown in Table IV.

Table IV

Run No.	7	8	Original oil
Amount of solvent	434	548	—
Mole percent of carbon dioxide in solvent	68-70	66-68	—
Amount of oil dissolved	41.6	74.0	100
Properties of dissolved oil:			
Specific gravity d_{40}^{20}	0.9357	0.9553	0.9796
Refractive index n_D^{20}	1.5208	1.5342	1.5561
Viscosity, seconds Saybolt Universal:			
At 100° F.	971.7	3085	17,376
At 210° F.	68.6	109	256.2
Viscosity index	28	4	—7
Color, A. S. T. M.	5-D	8-D	Black
Viscosity gravity constant	0.877	0.893	0.911

The nature of the separation effected is again seen to be partly on the basis of molecular size and partly on the basis of chemical structure, the more saturated or paraffinic hydrocarbons of lower molecular sizes being preferentially dissolved in the solvent. The effect of the composition is also apparent, for while in run 8 only 26% more solvent was employed than in run 7, the effect of employing a solvent containing carbon dioxide in lower concentration resulted in the extraction of 78% more oil. It should be noted that the solubility of the oil in the solvent mixture was about 10% in run 7 and 14% in run 8, these values being much greater than 0.2%, as given in Table III.

While in the foregoing examples various compositions of the solvent mixture containing from about 65 to 89 mole percent of carbon dioxide were employed, it is understood that the present invention is not restricted to such proportions, but may be used with other concentrations of carbon dioxide, depending upon the hydrocarbon diluent and the quantity of the solvent employed. Thus, when liquid propane or liquid ethane or their mixture is employed, considerably lower concentration of carbon dioxide, often as low as or lower than 25 mole per cent, may be employed. In general, my preferred range of concentrations of carbon dioxide in the solvent mixture is from about 25 to 95 mole per cent, although my invention is not restricted to this range. The ratio of the weight of the solvent mixture to oil, similarly, may be varied in accord-

ance with the quantity which it is desired to extract. By way of example, it may be stated that ratios of between 1.5 and 6.0 will most usually be employed.

Although I have already disclosed the distillation as a method of separating CO₂ from the oil and from the diluent, it is often advantageous to employ a chemical treatment for this purpose. For instance, for removing the last traces of CO₂ from the treated oil it may be subjected to a treatment with an aqueous solution of a caustic alkali metal or an organic base, like alkylamines, or of a salt capable of extracting CO₂. It is particularly advantageous to employ for this purpose aqueous solutions of reagents which can be readily regenerated by releasing the absorbed CO₂ upon heating and reused. Examples of the suitable processes are described in the Rosenstein Patent 1,945,163 and patent application Serial No. 25,947, filed June 10, 1935. This process may be substituted for instance, for the distilling apparatus 11 and 14 or 24 and 26 of Figure 1, whereby CO₂ and diluent are separated from each other in a continuous manner and returned to their respective receiving tanks.

I claim as my invention:

1. A process for refining oils by extraction with a light hydrocarbon solvent modified with liquid carbon dioxide comprising contacting said oil with a liquid selective solvent consisting substantially of carbon dioxide and light aliphatic hydrocarbons of six or less carbon atoms per molecule, there being no overlapping in boiling range between the lightest fraction of said oil and said light hydrocarbon solvent, maintaining a pressure sufficient to keep the solution of oil and solvent in the liquid phase during the contacting, and producing two liquid phases, one comprising a solution of a portion of said oil in said selective solvent and the other consisting essentially of an undissolved portion of said oil containing a relatively small portion of said solvent.

2. The process according to claim 1 in which a relatively heavy hydrocarbon fraction is extracted to manufacture lubricating oils.

3. The process according to claim 1 in which the lighter phase is extracted for a second time with a similar solvent containing different ratios of carbon dioxide and liquid normally gaseous hydrocarbon to cause its separation into second liquid phases and separating said second liquid phases.

4. The process according to claim 1 in which the streams of heavy petroleum fraction and solvent are flown countercurrently.

5. The process according to claim 1 in which carbon dioxide and liquid normally gaseous hydrocarbon are evaporated from the lighter phase and after being liquefied are returned and brought into contact with an additional quantity of oil.

VERNON LANTZ.
